UNITED STATES PATENT OFFICE.

ARCHIBALD M. McCREA, OF PITTSBURG, PENNSYLVANIA, ASSIGNOR TO UNION SPRING AND MANUFACTURING COMPANY, OF PITTSBURG, PENNSYLVANIA, A CORPORATION OF PENNSYLVANIA.

AXLE-BOX LID.

No. 804,873.

Specification of Letters Patent.

Patented Nov. 21, 1905.

Application filed October 26, 1904. Serial No. 230,097.

To all whom it may concern:

Be it known that I, ARCHIBALD M. McCREA, a resident of Pittsburg, in the county of Allegheny and State of Pennsylvania, have invented a new and useful Improvement in Axle-Box Lids; and I do hereby declare the following to be a full, clear, and exact description thereof.

My invention relates to lids for axle and similar boxes, and has for its object to provide a lid which is imperforate, so as to exclude dust and dirt and prevent the oil from escaping, and which is so constructed that the spring for holding the lid shut can be readily inserted and removed therefrom.

In the accompanying drawings, Figure 1 is a perspective view of a car-axle box provided with my improved lid. Fig. 2 is a vertical section through the same. Fig. 3 is an inside perspective view of the lid, and Fig. 4 is a perspective view of the spring.

The axle-box is shown at 1, and this is or may be of the usual or any desired form. It is provided with the usual lug 2 for receiving the hinge bolt or pintle 3 of the lid. This lug has its forward face 4 so formed as to provide a cam or shoulder against which the upper end of the spring bears, thereby to hold the axle-box lid closed, as is now the practice, and will be understood without further description.

The lid is shown at 5, and this also may be of the usual or any preferred form. Preferably it will be made by stamping or pressing a metal plate to form, although my invention is not limited in this particular, but applies also to a cast lid. This lid is provided at its upper end with the hinge-eyes 6 for receiving the hinge-bolts 3 and is also provided at the upper edge with the outward bulge or hooded portion 7 to provide a space for the spring. Below this central hooded portion the lid is provided with the outwardly-bulging socket or recess 8 to provide a seat for the lower end of the spring. On the inner face of the lid and lying across the socket or recess 8 is a suitable bridge-piece 9, which is formed as a stirrup or staple, having its ends inserted through openings in the lid and riveted or upset therein, as indicated at 10.

The spring 11 is an ordinary flat leaf-spring and is located in the hood 7 with its upper end bearing against the cam or shoulder 4 of

the axle-box. The lower end of this spring projects down into the socket or recess 8 and is held between the stirrup 9 and the outer wall of said socket. To prevent the spring from rising or falling, it is provided with suitable projections, one of which is arranged to bear against the under side of the stirrup 60 and the other to bear against the upper side thereof, the former preventing the spring from jumping up or rising and the latter preventing the spring from falling down. These projections may be of various forms, being 65 either bosses or lugs attached to or formed on the spring in any suitable way. Preferably, however, they will be formed by suitably bending the spring. Accordingly, the lower end of the spring is bent into the form of a 70 hook 11^a, which will lie underneath the stirrup 9 and prevent the spring from rising. Just above the stirrup the body of the spring is also bent inwardly to form the projection 12, which will lie just above the stirrup and 75 prevent the spring from dropping. By these simple means the spring is held effectually in place and cannot get out of place by the jar-ring of the car-truck. The projections 11^a and 12 fit the stirrup accurately, so that the 80 spring can neither rise nor drop, even for a short distance, nor can it swing sidewise out of perpendicular position. As a consequence the effectiveness of the spring is uniform at all times. At the same time when the lid is 85 removed from the box the spring can be very readily removed, so as to facilitate the replacement of broken or lame springs.

The lid itself is imperforate, so as to effectually exclude dust and dirt from the axle- 90 box and also prevent the escape of oil contained in the axle-box. The lid can be shaped at a single operation by suitable pressing-dies, and the spring can be likewise so shaped prior to tempering, so that the cost of manufacture 95 is small.

I wish it understood that the exact form of spring and stirrup shown need not be employed, but that any suitable bridge-piece extending across the socket will answer my 100 purpose, and also that the projecting portions 11^a and 12 on the spring need not be integral with the spring, but may be suitable lugs secured to the spring, or, if desired, 105 they may be merely teats or tongues punched out from the metal of the spring.

What I claim is—

1. The combination of an imperforate axle-box lid having hinge-eyes at its upper end, a stirrup or staple on the inner face of the lid, and a flat leaf-spring having its end inserted and held between the stirrup and lid, the inner face of the lid opposite the lower end of the spring being substantially straight vertically and the spring having projecting portions on its inner face adapted the one to bear on the top of the stirrup and the other against the bottom of the stirrup, whereby said spring is held by said projections both from falling and rising.
- 15 2. The combination of an imperforate axle-box lid having hinge-eyes at its upper end, a stirrup or staple on the inner face of the lid, and a flat leaf-spring having its end inserted and held between the stirrup and the lid, the inner face of the lid opposite the lower end of the spring being substantially straight vertically and said spring having its lower end bent inwardly and adapted to lie below the stirrup and having an inwardly-projecting portion above said lower end adapted to bear against the upper side of said stirrup, whereby said spring is held by said inwardly-projecting portions both from falling and rising.
- 20 3. The combination of an imperforate axle-box lid having hinge-eyes at its upper end and a socket or recess below said upper end, said socket or recess having its inner face substantially straight vertically, a bridge-piece extending across said socket on the inner face of the lid, and a flat leaf-spring having its end inserted and held between the stirrup and the lid having its end inserted and held between the socket-wall and said bridge-piece and having its lower end bent inwardly and adapted to lie below the bridge-piece, and an inwardly-projecting portion above its lower end adapted to lie above said bridge-piece.
- 25 4. The combination of an imperforate axle-box lid having hinge-eyes at its upper end and a socket or recess below said upper end, said socket or recess having its inner face substantially straight vertically, a bridge-piece extending across said socket on the inner face of the lid, and a flat leaf-spring having its end inserted and held between the stirrup and the lid having its end inserted and held between the socket-wall and said bridge-piece and having its lower end bent inwardly and adapted to lie below the bridge-piece, and an inwardly-projecting portion above its lower end adapted to lie above said bridge-piece.
- 30 5. The combination of an imperforate axle-box lid having hinge-eyes at its upper end and a socket or recess below said upper end, said socket or recess having its inner face substantially straight vertically, a stirrup bridged across said socket on the inner face of the lid, and a flat leaf-spring having its end inserted and held between the stirrup and the lid having its end inserted and held between the socket-wall and bridge-piece and having a hooked lower end adapted to lie underneath the stirrup and an inwardly-bent portion above its lower end adapted to lie above said stirrup.
- 35

In testimony whereof I, the said ARCHIBALD M. McCREA, have hereunto set my hand.

ARCHIBALD M. McCREA.
